UNITED STATES PATENT OFFICE.

JACOB W. C. WILLIAMS, OF PALCO, KANSAS.

PEN AND PENCIL RACK.

1,319,743.

Specification of Letters Patent.

Patented Oct. 28, 1919.

Application filed December 19, 1918. Serial No. 267,519.

To all whom it may concern:

Be it known that I, JACOB W. C. WILLIAMS, a citizen of the United States, residing at Palco, in the county of Rooks and 5 State of Kansas, have invented certain new and useful Improvements in Pen and Pencil Racks, of which the following is a specification.

This invention relates to desk attachments, and more particularly to racks for supporting pens, pencils and the like.

The object of the invention is to provide a device of this character so constructed that the pens and pencils thereon can be 15 readily grasped by the fingers in the middle without interference by the support.

Another object is to provide such a rack which will occupy a small space and may be suspended from a wall or other support 20 and used to contain pads, blotters, stationery, et cetera, as well as pens and pencils.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 30 within the scope of what is claimed without departing from the spirit of the invention.

In the accompanying drawings:

Figure 1 represents a side elevation of a 35 rack constructed in accordance with this invention shown in operative position,

Fig. 2 is a front elevation thereof, and

Fig. 3 is a horizontal section taken on the line 3—3 of Fig. 1.

In the embodiment illustrated, the rack constituting this invention is shown mounted on a support S and comprises two side bars 1 and 2 arranged parallel and connected at their lower ends by a plate or cross 45 bar 3, U-shaped in cross section, with the side flanges 4 thereof extended inwardly, as is shown clearly in Fig. 1, the distance between the flanges corresponding to the width of the side bars.

The upper ends of the bars 1 and 2 are connected by a plate 5, the rear upper corners of said bars being beveled as shown at 6, and said plate extended over the upper

ends of the bars and over said beveled portions as is shown clearly in Fig. 1. This 55 plate 5 is preferably apertured as shown at 7 to adapt the rack to be suspended from nails, hooks or the like.

Hook-shaped hangers 8 are also carried by the upper ends of the bars 1 and 2 and 60 are designed to be hooked over the support S as is shown clearly in Figs. 1 and 2. It will thus be seen that this rack may be suspended in various ways from a support.

The side bars 1 and 2 are provided on 65 their inner faces with longitudinally spaced, transversely arranged grooves 9, each of which has a centrally disposed socket 10 to receive the ends of supporting shelves soon to be described.

Any desired number of shelves 11 may be used, thirteen being here shown, although 70 obviously the number may be varied. Each of these shelves is composed of spring wire 75 bent into U-shaped form, the legs 12 of which are composed of parallel members 13 and 14, the outer members 14 having outwardly extending rightangularly disposed fingers 15 which are designed to enter the sockets 10 and hold the shelves in adjusted position, the legs or rather the outer members 14 of said legs, lying in the grooves 80 9 so that the shelves cannot pivot when so positioned. The cross bar 16 of the shelves 11 are arranged substantially in 85 alinement with the fingers 15 and when the shelves are engaged with the side bars, as shown clearly in Fig. 3, these bars 16 will be arranged in the space between the side bars 1 and 2, and the legs 12 project at right 90 angles to said bars, as is shown clearly in Figs. 1 and 3.

One of the shelves 11 is preferably arranged in inverted position near the lower end of the connected side bars so that the 95 legs 12 thereof will project in a direction opposite to the shelves on the other face and are designed to act as spacers for holding the lower end of the rack away from the support S, as is shown clearly in Fig. 100 1, the beveled faces 6 of the upper ends of the side bars, resting flat against said support, so that the rack will be held suspended at an incline to facilitate the placing and removal of articles to be carried thereby.

The ends of the legs 12 are made in the

form of connecting rods 17 arranged at right angles to the side members 13 and 14, and connecting said members so that they will rest flat against the support S to hold the rack against wobbling, it being of course understood that the two legs are of equal length.

From the above description it will be obvious that a rack constructed as shown and described herein, will be very simple in construction, and the shelves 11 being removable are also adjustable or rather interchangeable, so as to vary the space between the shelves, it being obvious that each of the pairs of oppositely disposed grooves 9 may support a shelf or the shelves may be positioned in any desired pair of grooves, so that the spaces between them may be varied.

By referring to Fig. 3 it will be obvious that to remove a shelf, all that is necessary is to compress the legs 12 toward each other a sufficient distance to release the fingers 15 from the sockets 10 and disengage the members 14 from the grooves 9 when the shelf may be readily removed and placed at another position. When positioning a shelf, the fingers 15 are engaged with the sockets 10 and will spring automatically into place, that is, the members 14 will spring into the grooves 9 and hold the shelf firmly in operative position.

Pens and pencils may be placed on these respective shelves and are indicated in Fig. 1 by the dotted lines 18, also in Fig. 3. When it is desired to remove a pencil or pen, the middle portion thereof may be grasped without interference of the support and readily removed without removing any of the others, even though each shelf may contain a number.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention, and may be made of any suitable material.

Having thus fully described my invention,

what I claim as new and desire to secure by Letters Patent, is:—

1. A rack of the class described comprising a pair of laterally spaced parallel bars with longitudinally spaced transversely extending grooves on their inner opposed faces, connectors for the ends of said bars, and a plurality of pairs of spring fingers yieldably held in said grooves. 60

2. A rack of the class described comprising a pair of parallel laterally spaced bars with a plurality of longitudinally spaced transversely extending grooves on their inner opposed faces, each groove having a socket extending inwardly therefrom, connectors for the ends of said bars, U-shaped supports having outwardly projecting fingers at their free ends adapted to be engaged with said sockets and the legs thereof to enter said grooves whereby said supports are held firmly in position. 70

3. A rack of the class described comprising a pair of parallel laterally spaced bars, members rigidly connecting the ends of said bars, the upper ends of said bars being beveled on their rear corners and having suspending means, and a plurality of detachable supports carried by the bars and projecting outwardly therefrom, and lateral projections on the rear face of the lower end of said bars whereby the rack is held in inclined position when suspended. 80

4. A rack of the class described comprising laterally spaced supporting bars rigidly connected at their ends, means for holding said bars in inclined position when suspended, and article supports detachably engaged with said bars and each comprising a U-shaped member having the legs thereof composed of parallel spaced bars, the outer bars having outwardly extending right-angledly disposed fingers at the ends adjacent to the cross bar of said supports. 90

5. A rack of the class described having a plurality of adjustably mounted shelves, each composed of spring wire bent to U-shape form, the legs of which comprise parallel members spaced laterally apart with outwardly extending fingers at the free ends of their outer members. 100

In testimony whereof I affix my signature in presence of two witnesses.

JACOB W. C. WILLIAMS.
